UNITED STATES PATENT OFFICE.

JOHN W. RADU, OF NEW YORK, N. Y., ASSIGNOR TO WESTERN ELECTRIC COMPANY, INCORPORATED, OF NEW YORK, N. Y., A CORPORATION OF NEW YORK.

VACUUM-TUBE SOCKET.

Application filed December 16, 1920. Serial No. 431,224.

To all whom it may concern:

Be it known that I, JOHN W. RADU, a citizen of United States, residing at New York, in the county of New York, State of New York, have invented certain new and useful Improvements in Vacuum-Tube Sockets, of which the following is a full, clear, concise, and exact description.

This invention relates to a device for establishing electrical connections and pertains more especially to a socket for vacuum tubes.

It is an object of this invention to construct a vacuum tube socket in which the design and arrangement of its elements are such as to produce a simple and very compact structure. To accomplish this object there is provided a cylindrical shell within which is detachably arranged a disc by which are carried electrical conductors projecting from one face thereof. Contact members adapted to engage the terminals of a vacuum tube are mounted on the disc and are electrically connected with said conductors which are connected with the circuits for a vacuum tube.

This invention will be better understood by having reference to the following specification and accompanying drawing where-in Fig. 1 discloses a socket partially broken away with the vacuum tube in place and Fig. 2 is an enlarged perspective view of the disc.

A cylindrical shell 10 is provided at one end with a bayonet slot and in the opposite enlarged end are cut screw threads 12. Intermediate the ends of the shell is provided an annular shoulder 13. Arranged to abut against the shoulder 13 is a disc 14 preferably of insulating material which is held against the shoulder by a screw threaded sleeve 15 carried by the base 16 having lugs or the like, by means of which it may be attached to a support. The disc 14 is provided with a slot 17 which is adapted to cooperate with a lug 18 on the interior of the shell to locate and maintain the disc in a predetermined position relative to the shell. The disc is also provided with slots 19 at regular intervals around the periphery of the disc. Contact members 20 formed from straight lengths of resilient metal bent to form bow portions intermediate their ends are carried by the

disc 14 with their bow portions located in slots 19 and their ends on opposite sides of the disc. Bolts 21 which extend through the disc and project beyond the face thereof pass through apertures in certain ends of said contact members 20 and nuts 22 serve to clamp said ends of the contact members against the disc. The opposite ends of the contact members are spaced slightly from the face of the disc and are adapted to yield when pressure is applied thereto. The arrangement of the slots 19 and the contact members 20 is such that each of said contact members lies at right angles to the adjacent contact members and parallel to the remaining contact member and the terminals of said contact members form the corners of a square. This arrangement gives to the free leg of each of the contact members the longest length possible consistent with the diameter of the disc and the number of contact members required. To the lower end of the bolts 21 are attached the ends of the circuit wires for a vacuum tube which wires pass through an aperture in the base 16.

The arrangement of the slot 17, lug 18 and contact members 20 is such that when the disc is positioned within the shell, the ends of the contact members engage the terminals 23 of a vacuum tube 24 inserted in the socket. The vacuum tube is located and retained in the socket by engagement with the pin 25 of the vacuum tube base in the bayonet slot 11 in the shell, the resiliency of the contact members 20 serving to maintain such engagement.

What is claimed is:

A vacuum tube socket comprising a shell, a disc of insulating material arranged within said shell, a plurality of contact members, each contact member having one end attached to one side of said disc and comprising a resilient strip bent to form a bow portion with its ends in alignment, the free end of each contact member being spaced from the opposite face of said disc, each contact member being arranged at right angles to the adjacent contact members and along a chord of the disc.

In witness whereof, I hereunto subscribe my name this 11th day of December A. D., 1920.

JOHN W. RADU.
